United States Patent Office

Des. 181,312
Patented Oct. 29, 1957

181,312

SLIDE PROJECTOR

Anton G. Parisson, Brentwood, and Donald J. Behnk,
Whitehall, Pa., assignors to Bausch & Lomb Optical
Company, Rochester, N. Y., a corporation of New
York

Application February 20, 1957, Serial No. 44,927

Term of patent 14 years

(Cl. D61—1)

FIG. 1

FIG. 2

FIG. 3

Fig. 1 is a front perspective view of a slide projector showing our new design.

Fig. 2 is a rear perspective view thereof.

Fig. 3 is a front elevational view thereof.

The characteristic features of the design are shown in full lines on the drawing.

We claim:

The ornamental design for a slide projector, substantially as shown and described.
